UNITED STATES PATENT OFFICE

172,545

GAME BOARD

Elmer F. Kumpf, Jennings, Mo., assignor to
Northwestern Mail Box Company, St. Louis,
Mo., a corporation of Missouri

Application March 29, 1954, Serial No. 29,718

Term of patent 7 years

(Cl. D34—5)

To all whom it may concern:

Be it known that I, Elmer F. Kumpf, a citizen of the United States, residing in the city of Jennings, county of St. Louis, and State of Missouri, have invented, a new, original, and ornamental Design for a Game Board, of which the following is a specification, reference being had to the accompanying drawing, forming a part thereof.

In the drawing:

Fig. 1 is a top plan view of a game board embodying my new design;

Fig. 2 is a bottom plan view of the said game board;

Fig. 3 is a sectional view as taken at line 3—3 of Fig. 1, and

Fig. 4 is a sectional view as taken at line 4—4 of Fig. 1.

I claim:

The ornamental design for a game board, substantially as shown.
